UNITED STATES PATENT OFFICE.

EDWARD E. ROSE, OF SWISSVALE, AND CHARLES A. SMITH, OF EDGEWOOD PARK,
PENNSYLVANIA, ASSIGNORS TO WESTINGHOUSE ELECTRIC & MANUFACTURING
COMPANY, A CORPORATION OF PENNSYLVANIA.

CONTROL APPARATUS.

1,401,647.

Specification of Letters Patent. Patented Dec. 27, 1921.

Application filed October 6, 1919. Serial No. 328,823.

To all whom it may concern:

Be it known that we, EDWARD E. ROSE, a citizen of the United States, and a resident of Swissvale, in the county of Allegheny, and State of Pennsylvania, and CHARLES A. SMITH, a citizen of the United States, and a resident of Edgewood Park, in the county of Allegheny and State of Pennsylvania, have invented a new and useful Improvement 10 in Control Apparatus, of which the following is a specification.

Our invention relates to control apparatus and especially to controllers of the drum type that are actuated by power devices.

15 The object of our invention is to provide a relatively compact combined apparatus of the above-indicated character wherein a fluid-pressure-operated actuating mechanism, for example, has a direction of movement transverse to that of the drum controller and embodies power-transmitting means that are arranged in side-by-side relation in the same plane.

More specifically stated, it is the object 25 of our invention to provide a power-operated actuating apparatus for a drum type controller that extends substantially parallel to the axis of the drum, and power-transmitting means in the form of spiral or helical 30 gear-wheels for operatively connecting the apparatus to the drum, the axes of the gear-wheels being substantially parallel to the axis of the control drum.

In the prior art, combined apparatus of 35 the type under consideration has customarily involved the use of fluid-pressure-operated apparatus, or the equivalent, that has been located upon one end of the controller and has operated in the same direction as the drum. The resultant structure has, in general, been of irregular shape and non-compact structure which has entailed considerable additional time and labor during both the manufacture and installation 40 of the apparatus and also in the subsequent operating maintenance thereof.

According to our present invention, the drum controller and the power apparatus, both of substantially cylindrical general 50 shape, are located side-by-side within a controller case of a regular rectangular form, and all the power-transmitting means are

located in side-by-side relation in the same plane. Arranged in this way, the entire apparatus requires a minimum amount of 55 mounting space, is neat and compact in appearance and is readily accessible for inspection and maintenance by merely removing the front incasing member of the type that is usually employed in connection 60 with the well-known K controllers.

Our invention may best be understood by reference to the accompanying drawings, wherein—

Figure 1 is a view, in plan, of a drum-controller apparatus constructed in accordance with our present invention; 65

Fig. 2 is a view, chiefly in longitudinal section and partially in elevation, of a drum controller and power-operated actuating apparatus therefor constructed and arranged 70 in accordance with our invention;

Fig. 3 is a view, chiefly in end elevation and partially in section, of the apparatus 75 that is shown in Fig. 1; and

Fig. 4 to Fig. 14, inclusive, are detail views serving to more clearly illustrate the various parts of the operating mechanism.

Referring to the drawings, the apparatus 80 here shown comprises a controller frame or back 1 and a removable incasing member 2, which is provided with a hinge connection 3 and a latching device 4, on opposite sides, for attachment to the frame member, the 85 resulting box or chamber being divided into two compartments 5 and 6 which are, in part, separated by a partition or barrier 7 that is suitably secured to the frame 1. A notching relay 8 is mounted upon the partition 7 within the compartment 5, while the major compartment 6 is occupied by a device 9 comprising our novel power-operated 90 actuating apparatus for controller drums.

Since the notching relay 8, although employed in conjunction with the electrical control of the controlling device 9, forms no part of our present invention, it is not deemed necessary to further describe the relay. 95

Referring, therefore, to the device 9, this apparatus comprises a power-operated piston and cylinder mechanism 15 which is electrically controlled through the agency of a 100

plurality of magnet valves 16 and 17 located at opposite ends of the apparatus, whereby a plurality of drum controllers 18 and 19 are actuated through the medium of a power-transmitting mechanism 20.

A suitable stirrup or cradle 21 for supporting the power-operated apparatus 15 is secured by a plurality of bolts 22 to the controller frame 1. Positioned within the cradle 21 are a plurality of aligned cylinders 23 and 24 within which a pair of piston members 25 and 26 are adapted to operate, being rigidly bolted to the ends of a rack member 27, one side of which is provided with a plurality of spiral or helical teeth 28, as best shown in Fig. 14.

The magnet valve 16 embodies a double-plug valve member 29 which is normally adapted to effect communication between the operating cylinder 23 and the atmosphere and is further adapted, when lifted through the agency of the energization of an actuating coil 30, to admit air or other fluid medium under pressure from a supply pipe 31 to the cylinder 23.

On the other hand, the magnet valve 17 comprises a double-plug valve member 32 which is normally adapted to admit air under pressure from a supply pipe or passage 33 to the operating cylinder 24 and, when actuating coil 34 is energized, the valve member 32 is adapted to cut off such normal fluid communication and effect the release of air under pressure from the operating cylinder 24 to the atmosphere.

By reason of the initial presence of fluid under pressure in the operating cylinder 24, whereas atmospheric pressure obtains in the other cylinder 23, the piston members 25 and 26 are biased to the extreme position that is illustrated in Fig. 2.

For supplying air or other fluid medium under pressure to the pipes or passages 31 and 33, a suitable delivery pipe 35 extends within the controller case substantially parallel to the axis of the operating cylinders and is pneumatically connected in any suitable manner with an external source of fluid pressure (not shown).

A plurality of sets of control fingers 41 and 42 are adapted to engage suitable contact segments (not shown) upon the respective drums 18 and 19 for effecting the desired control of the external circuits, as will be understood without further elucidation. Although the particular drums that we have illustrated are adapted to control auxiliary circuits carrying small current, it will be appreciated that our invention is not so limited in its application and any drum of greater capacity or, in fact, cams for operating switches may be substituted for the illustrated drums 18 and 19.

A shaft 43 extends the entire length of the two aligned drums 18 and 19 and its inter-

mediate portion is inclosed within bearing openings 44 in two similar caps or journals 45, one of which is shown in detail in Fig. 8 and Fig. 9. The drums 18 and 19 are thus of the overhanging type, being supported only at the central portion of their operating shaft 43. In this way, a compact and inexpensive drum arrangement is provided, since bearings or pedestals for the outer ends of the drums are not necessary.

Rigidly secured to the shaft 43 between the drums 18 and 19, is a spiral or helical pinion 46 which meshes with an aligned second helical or spiral pinion 47, the operating shaft 48 of which extends parallel to the drum shaft 43 and the rack member 27. The shaft 48 is located in bearing openings 49 that pierce a bracket or standard 50 that is shown in detail in Fig. 10, Fig. 11 and Fig. 12. The spiral gears 46 and 47 are shown in detail in Fig. 4 to Fig. 7, inclusive.

Referring to the detail views of the bracket 50, (Fig. 10, Fig. 11 and Fig. 12), this bracket is of general U-shape in the view that is shown in Fig. 2 and in Fig. 10, comprising a base or body portion 56 which has four symmetrically located bolt openings 57 that register with corresponding openings 57a in the two caps or journals 45. Suitable bolts 58 serve to secure the journals 45 to the bracket member 50 and thus rigidly position the spiral pinion 46 and the drums 18 and 19. The opposite end of the bracket member 50 comprises four arms 59 which, as clearly shown in Fig. 3, act as 100 guide members for the sliding rack 27. A pair of laterally extending lugs or arms 60 are provided near one pair of the guide members 59, while a corresponding pair of lugs 61 are located near the opposite pair of guide members. A plurality of bolts 62 and 63, shown in Fig. 3, serve to secure the bracket members 50 to the stirrup or saddle 21, whereby the spiral pinion 47 is rigidly positioned to properly mesh with the spiral rack member 27.

It will be seen that we have thus provided a relatively compact and self-contained drum controller and power-operated actuating apparatus therefor, wherein the axes of the drums and of the operating cylinders extend in substantially parallel lines, while the axes of the spiral pinions not only extend also in parallel relation to the drum axis, but all the axes in question are located in the same plane, as is clearly evident from the sectional view of Fig. 3.

The operation of our apparatus may be set forth as follows. Upon concurrent energization of the actuating coils 30 and 34, the initial unbalanced fluid-pressure conditions in the operating cylinders are reversed, that is, fluid under pressure is admitted through the magnet valve 16 to the operating cylinder 23 and is released from the operating

cylinder 24 through the magnet valve 17. Consequently, the piston members 25 and 26 and the rack 27 move toward the right, when considering the structure shown in Fig. 2, whereby the helical or spiral teeth 28 on the rack cause the meshing pinion member 47 to rotate in a clockwise direction, viewed from the right-hand end of Fig. 2, and the other spiral pinion 46 rotates in a counter-clockwise direction to effect the desired rotative movement of the drums 18 and 19.

To arrest such movement, at any time, it is merely necessary to deenergize the magnet valve 17, whereupon balanced high-pressure conditions obtain in the two operating cylinders 23 and 24, and the desired stoppage is positively and reliably effected.

To produce a return movement of the apparatus to the illustrated position, the magnet valves 16 and 17 are concurrently deenergized, whereupon fluid-pressure conditions in the apparatus revert to the original unbalanced state, and the desired backward movement is effected.

We do not wish to be restricted to the specific structural details or arrangement of parts herein set forth, as various modifications thereof may be made without departing from the spirit and scope of our invention. We desire, therefore, that only such limitations shall be imposed upon our invention as are indicated in the appended claims.

We claim as our invention:

1. In a controller, the combination with a movable control member, of a power-operated actuating apparatus therefor having a direction of movement transverse to the plane of rotation of said member, and power-transmitting means interposed between said apparatus and said member and comprising a plurality of elements arranged in side-by-side relation.

2. In a controller, the combination with a rotatable control member, of a power-operated actuating apparatus extending substantially parallel to the axis of said member, and a plurality of meshing gear-wheels arranged in side-by-side relation and respectively secured to said apparatus and to said member.

3. In a controller, the combination with a movable control member, of an electrically-controlled, fluid-pressure-operated actuating apparatus therefor having a direction of movement transverse to the plane of rotation of said member, and a plurality of power-transmitting members arranged in side-by-side relation and interposed between said apparatus and said member.

4. In a controller, the combination with a rotatable control member, of a fluid-pressure-operated actuating apparatus therefor extending substantially parallel to the axis of said member, and a plurality of meshing

gear-wheels for transmitting power from said apparatus to said member, said gear-wheels having substantially parallel axes.

5. In a controller, the combination with a rotatable control member, of a power-operated actuating apparatus therefor extending substantially parallel to the axis of said member, and a plurality of meshing gear-wheels for transmitting power from said apparatus to said member, said gear-wheels having axes substantially parallel to the axis of the control member.

6. In a controller, the combination with a rotatable control member, of a power-operated actuating apparatus therefor having a direction of movement transverse to the plane of rotation of said member, and a plurality of meshing gear-wheels respectively secured to said apparatus and said member and having axes substantially parallel to the axis of the control member.

7. In a controller, the combination with a rotatable control member, of a power-operated actuating apparatus therefor extending substantially parallel to the axis of said member and comprising a spiral rack and meshing pinion, and a second pinion meshing with the other and secured to said control member.

8. In a controller, the combination with a rotatable control member, of a power-operated actuating apparatus therefor extending substantially parallel to the axis of said member and comprising a spiral rack and meshing pinion, and a second pinion meshing with the other and secured to said control member, the axes of said rack and said pinions being in the same plane.

9. In a controller, the combination with a rotatable control member, of an electrically-controlled, fluid-pressure-operated actuating apparatus therefor extending substantially parallel to the axis of said member and comprising a spiral rack and meshing pinion, and a second pinion meshing with the other 110 and secured to said control member.

10. In a controller, the combination with two movable control members, of a power-operated actuating apparatus therefor, power-transmitting means interposed between said apparatus and a point intermediate said control members, and supporting means for said power-transmitting means constituting the sole support for said control members.

11. In a controller, the combination with a pair of aligned movable control members, of a power-operated actuating apparatus therefor having a direction of movement transverse to the plane of rotation of said members, power-transmitting means having a plurality of elements arranged in side-by-side relation and interposed between said apparatus and a point intermediate said control members, and supporting means for said

power-transmitting means constituting the sole support for said control members.

12. In a controller, the combination with a pair of alined rotatable control members, of a power-operated actuating apparatus extending substantially parallel to the axis of said members, a plurality of meshing gear-wheels arranged in side-by-side relation and respectively secured to said apparatus and between said members, and supporting means for said gear-wheels constituting the sole support for said control members.

13. In a controller, the combination with a pair of alined rotatable control members, of a power-operated actuating apparatus therefor extending substantially parallel to the axis of said members, a plurality of meshing gear-wheels for transmitting power from said apparatus to a point between said control members, said gear-wheels having axes substantially parallel to the axis of said control members, and a supporting bracket device for said gear-wheels constituting the sole support for the control members.

14. In a controller, the combination with a pair of alined rotatable control members, of a power-operated actuating apparatus therefor extending substantially parallel to the axis of said members and comprising a spiral rack and meshing pinion, a second pinion meshing with the other and secured between said control members, and a sup-

porting journal device for said pinions constituting the sole support for the control members.

15. In a controller, the combination with a pair of alined rotatable control members, of a power-operated actuating apparatus therefor extending substantially parallel to the axis of said members and comprising a spiral rack and meshing pinion, a second pinion meshing with the other and secured between said control members, the axes of said rack and said pinions being in the same plane, and a supporting journal device for said pinions constituting the sole support for the control members.

16. In a controller, the combination with a pair of alined control drums, of a fluid-pressure - operated actuating apparatus therefor having an operating cylinder structure and a piston-actuated rack member, a pinion meshing with said rack member, a second pinion meshing with the other and secured between said control members, a supporting bracket for the first named pinion secured to said cylinder structure and a supporting journal for the other pinion secured to said bracket and constituting the sole support for said drums.

In testimony whereof we have hereunto subscribed our names this 4th day of Oct., 1919.

EDWARD E. ROSE.
CHARLES A. SMITH.
